NEEDLE THREADER FOR SEWING MACHINES

Emery J. Christoff, Johnstown, Pa.

Application November 29, 1949, Serial No. 129,928

8 Claims. (Cl. 112—225)

1

This invention relates to sewing machines and attachments therefor and more particularly to a needle threader which is adapted for use with standard makes of sewing machines.

An object is to provide a needle threader of the above type having novel and improved characteristics.

Another object is to provide a needle threader which can be operated with a minimum amount of manipulation and which is so simple and positive in operation that it can even be used by a sightless person.

Other objects and advantages will be apparent as the nature of the invention is more fully disclosed.

In one embodiment of the present invention a needle threading device is provided which is carried by the presser foot bar of the sewing machine and is normally held in a retracted position out of engagement with the needle. The device is so arranged that for threading the needle it is turned about the axis of the presser foot bar into engagement with the needle and at the same time is moved upwardly until stopped by the lower end of the needle bar. The stop means is so set that in this position a needle threading pin registers with the eye of the needle and is adapted to push the thread therethrough in response to a simple pressure of the finger. The device is accordingly simple and easy to operate and does not require that the needle bar be brought to a specified position prior to its actuation.

The various novel features which are characteristic of this invention will be better understood by referring to the following description, taken in connection with the accompanying drawings in which a specific embodiment thereof has been set forth for purposes of illustration.

In the drawings:

Fig. 1 is a side elevation of a portion of a sewing machine head illustrating the needle threader in retracted position on the presser foot bar;

Fig. 2 is a front elevation thereof;

Fig. 3 is a horizontal section taken on the line 3—3 of Fig. 1;

Fig. 4 is a vertical section taken on the line 4—4 of Fig. 2;

Fig. 5 is a horizontal section taken on the line 5—5 of Fig. 6 with a portion of the needle bar broken away to show the threader in contact with the needle;

Fig. 6 is a view of the lower portion of the sewing machine head, similar to Fig. 1, but on a larger scale;

2

Fig. 7 is a still larger vertical section taken on the line 7—7 of Fig. 6 showing the thread being pushed through the eye of the needle; and

Fig. 8 is a horizontal section taken on the line 8—8 of Fig. 6.

Referring to the drawings more in detail the invention is shown as applied to a standard sewing machine having a head 10, a presser foot bar 11 and a needle bar 12. The presser foot bar 11 carries a presser foot 13 which is adjustably secured thereto by a thumb screw 14 and cooperates with feed dog 15 to feed material past the path of the needle for stitching. The presser foot has the usual slot 41. The needle bar 12 carries a needle 16 of standard construction which is provided on one side with a longitudinal channel 17 to receive the thread and is provided at its lower end with an eye 18. The needle 16 is secured to the needle bar 12 by means of a thumb screw 19. The thread 20 is guided through thread guides 21 and 22 to the needle for stitching. The portion of the sewing machine thus far described is of standard construction and forms no part of the present invention and it is to be understood that the spacing and relative arrangement of the parts may vary somewhat in different makes of standard sewing machines.

The needle threader embodying the present invention comprises a bracket 25 having a cylindrical sleeve 26 which is adapted to fit loosely on the presser foot bar 11 and is of an axial length suited to permit limited vertical movement as well as rotational movement on the presser foot bar. The bracket 25 terminates at its forward end in a flange 26 to which a flat plate 27 is secured by means of set screws 28 and 29. The forward edges of the flanges 26 and of the plate 27 are bevelled to provide a vertical channel 29 and the bracket 25 is of such a size that when the threader is turned about the presser foot bar 11 into the position shown in Fig. 5 the channel 29a is brought into registration with the longitudinal channel 17 of the needle 16 to provide a thread-receiving and positioning recess.

A stop member 30 in the form of a flat plate is adjustably secured to the flange 26 by means of the set screw 28 and is provided with an elongated slot 31 to permit the vertical position of the stop member to be adjusted.

The flange 26 and the plate 27 are provided with registering transverse grooves 33 (Fig. 7) which form a hole to receive a pin 34. The pin 34 is positioned and adapted to pass through the eye 18 of the needle 16 and to force the thread 20 therethrough as shown in Fig. 7. At its for-

ward end the pin 34 is attached to a spring arm 36, the upper end of which is attached at 37 to the bracket 25. A strap 38 in the form of a hooked wire attached to the bracket 25 guides the arm 36 for movement in the plane of the pin 34. The arm 36 is adapted to normally hold the pin 34 retracted so that its point is entirely within the hole 33 and thereby protected from injury. The point is caused to protrude through the eye of the needle by pressing with the finger on the spring arm 36 or on the head of the pin 34 after the device has been properly positioned.

A detent 40, shown as a wire, is attached to the frame 26 by means of the set screw 29 and is adapted to rest on the knurled surface of the thumb screw 14 when the device is in retracted position as shown in Fig. 1.

The bracket 25 and the various elements constituting the threader are designed in accordance with the particular make of sewing machine to which the threader is to be applied. When used as an attachment, the presser foot 15 is first removed from the presser foot bar 11 by loosening the thumb screw 14, the sleeve 26 is positioned on the bar 11, and the presser foot is again attached. When the device is in retracted position it rests upon the knurled thumb screw 14 as above described and thus remains out of the path of the needle or of the needle bar.

The stop member 30 is first adjusted in accordance with the particular machine so that when the top surface of this member 30 engages the bottom of the needle bar 12, the pin 34 will be in exact registration with the eye 18 of the needle 16. Thereafter no further adjustment is required.

When it is desired to thread the needle the thread 20 is passed through the guides 21 and 22 and is held in the slot 41 of the presser foot bar 13. The threader is then manually lifted somewhat to clear the thumb screw 14 and is turned until the channeled edge 29 is in engagement with the needle 16. The device is also raised until the stop member 30 engages the bottom of the needle bar 12 (Fig. 6). When so positioned the channeled edge 29 of the device spans the thread 20 and holds the same against the channel 17 of the needle 16. Pressure of the finger on the spring arm 36 then causes the pin 34 to push the thread 20 through the eye of the needle as indicated in Fig. 7, after which the pressure on the spring arm 36 is released and the device is returned to the position shown in Fig. 1. The entire procedure may be carried out without actually viewing the position of the thread and hence the needle may be threaded readily in a dimly lighted room or even by a sightless person.

It is to be understood that the shape of the various parts and the mechanical details may be varied as desired. A specific embodiment has been shown for purposes of illustration only.

What is claimed is:

1. A sewing machine comprising a sewing machine head having a presser foot bar carrying a presser foot and a needle bar carrying a needle for stitching, said needle having an eye at its free end, a threading device comprising a bracket having a sleeve loosely journaled about said presser foot bar for limited vertical and rotational movement thereon, a vertical member carried by said bracket having a free vertical edge positioned to lie against and along the needle for positioning the thread when said device is rotated about said presser foot bar, a retractable pin extending transversely through said member

to register with the eye of said needle, spring means normally holding said pin retracted and adapted to permit said pin to be extended through said eye when located in registration therewith.

2. A sewing machine comprising a sewing machine head having a presser foot bar carrying a presser foot and a needle bar carrying a needle for stitching, said needle having a longitudinal side channel and an eye at its free end, a threading device comprising a bracket having a sleeve loosely journaled about said presser foot bar for limited vertical and rotational movement thereon, a vertical member carried by said bracket having a free vertical edge positioned to lie against and along the needle when said device is rotated about said presser foot bar, a retractable pin extending transversely through said member to register with the eye of said needle, spring means normally holding said pin retracted and adapted to permit said pin to be extended through said eye when located in registration therewith, said vertical edge of said member having a vertical channel adapted to receive and position said thread and to register with said needle channel, said pin being positioned to project through said channel and to engage the thread seated therein.

3. In combination with a sewing machine head having a presser foot bar carrying a presser foot and a needle bar carrying a needle for stitching, said needle having an eye at its free end, a threading device comprising a bracket having a sleeve loosely journaled about said presser foot bar for limited vertical and rotational movement thereon, a vertical member carried by said bracket having a free vertical edge positioned to lie against and along the needle for positioning the thread when said device is rotated about said presser foot bar, a retractable pin extending transversely through said member to register with the eye of said needle, spring means normally holding said pin retracted and adapted to permit said pin to be extended through said eye when located in registration therewith, a supporting member on said bracket and a member on said presser foot bar adapted to engage said supporting member to retain the device in retracted position.

4. In combination with a sewing machine head having a presser foot bar carrying a presser foot and a needle bar carrying a needle for stitching, said needle having a longitudinal side channel and an eye at its free end, a threading device comprising a bracket having a sleeve loosely journaled about said presser foot bar for limited vertical and rotational movement thereon, a vertical flange carried by said bracket having a free vertical edge positioned to lie against and along the needle when said device is rotated about said presser foot bar, a retractable pin extending transversely through said flange to register with the eye of said needle, spring means normally holding said pin retracted and adapted to permit said pin to be extended through said eye when located in registration therewith, a stop member carried by said flange to engage the under surface of said needle bar, said stop member being adjustable to position said pin into registration with said eye when said stop member engages said under surface, the forward edge of said flange having a vertical channel adapted to receive and position said thread and register with said needle channel, said pin being positioned to project through said channel to engage the thread seated therein.

5. An attachment for a sewing machine hav-

ing a head carrying a presser foot bar and a needle bar, said attachment comprising a bracket having a sleeve loosely journalled about said presser foot bar for limited vertical and rotational movement thereon, a vertical member carried by said bracket having a free vertical edge positioned to lie against and along the needle for positioning the thread when said device is rotated about said presser foot bar, a retractable pin extending transversely through said member to register with the eye of said needle, spring means normally holding said pin retracted and adapted to permit said pin to be extended through said eye when located in registration therewith.

6. An attachment for a sewing machine having a head carrying a presser foot bar and a needle bar, said attachment comprising a bracket having a sleeve loosely journalled about said presser foot bar for limited vertical and rotational movement thereon, a vertical member carried by said bracket having a free vertical edge positioned to lie against and along the needle when said device is rotated about said presser foot bar, a retractable pin extending transversely through said member to register with the eye of said needle, a spring means normally holding said pin retracted and adapted to permit said pin to be extended through said eye when located in registration therewith, said vertical edge of said member having a vertical channel adapted to receive and position said thread and to register with a similar channel in said needle, said pin being positioned to project through said channel and to engage the thread seated therein.

7. An attachment for a sewing machine having a head carrying a presser foot bar and a needle bar, said attachment comprising a bracket having a sleeve loosely journalled about said presser foot bar for limited vertical and rotational movement thereon, a vertical member carried by said bracket having a free vertical edge positioned to lie against and along the needle when said device is rotated about said presser foot bar, a retractable pin extending transversely through said member to register with the eye of said needle, spring means nor-

mally holding said pin retracted and adapted to permit said pin to be extended through said eye when located in registration therewith, a supporting member on said bracket and a member on said presser foot bar adapted to engage said supporting member to retain the device in retracted position.

8. An attachment for a sewing machine having a head carrying a presser foot bar and a needle bar, said attachment comprising a bracket having a sleeve loosely channelled about said presser foot bar for limited vertical and rotational movement thereon, a vertical flange carried by said bracket having a free vertical edge positioned to lie against and along the needle when said device is rotated about said presser foot bar, a retractable pin extending transversely through said flange to register with the eye of said needle, spring means normally holding said pin retracted and adapted to permit said pin to be extended through said eye when located in registration therewith, a stop member carried by said flange to engage the under surface of said needle bar, said stop member being adjustable to position said pin into registration with said eye when said stop member engages said under surface, said vertical edge of said flange having a vertical channel adapted to receive and position said thread and register with a similar channel in said needle, said pin being positioned to project through said channel to engage the thread seated therein.
